CLAIM

The ornamental design for a soap dish, substantially as shown and described.

DESCRIPTION

FIG. 1 is a perspective view of a soap dish showing my new design;

FIG. 2 is a front elevational view thereof; the rear being unornamented;

FIG. 3 is a top plan view thereof, the bottom being unornamented;

FIG. 4 is a right side elevational view thereof;

FIG. 5 is a top plan view of a second embodiment of the design of FIG. 1. The only difference being the inclusion of drainage holes.

FIG. 1

FIG. 2

FIG. 3

FIG. 4

FIG. 5
